(57) **CLAIM**

The ornamental design for a dental teeth device, as shown and described.

DESCRIPTION

FIG. 1 is a top view of a dental teeth device of the claimed design;

FIG. 2 is a front view thereof;

FIG. 3 is bottom view thereof;

FIG. 4 is a side view thereof;

FIG. 5 is a side view thereof; and,

FIG. 6 is a rear view thereof.

The ornamental design which is claimed is shown in solid lines in the drawings. The broken line drawings of a dental teeth device are for illustrative purposes only and form no part of the particular claimed design.
